APPARATUS FOR FORMING PELLETS

Sylvester A. Weigand and Anthony B. Monnig,
Cincinnati, Ohio, assignors to The Lunken-
heimer Company, Cincinnati, Ohio, a corpora-
tion of Ohio

Application August 2, 1949, Serial No. 108,207

4 Claims. (Cl. 18—2.5)

1

This invention relates to the art of grit blasting, and is directed particularly to an apparatus of producing metallic pellets or grit particles, adapted particularly to be propelled in a blast stream against the surfaces of metal objects such as castings which are to be cleaned thereby.

In recent years metallic particles of an abrasive nature have been used extensively in grit blasting operations in preference to finely divided sand which was commonly used in the past. Such metal grit has been produced heretofore by crushing metal of a frangible nature or by dropping molten particles of metal into a bath of water which chills them promptly so that the particles retain their integrality. In other instances molten metal is subdivided by slinging it from the face of a rotating disk. However, the shot produced by any of these methods has varied substantially in particle size, a large percentage of the grit being either too large or too small to be used extensively for grit blasting operations. Hence, extensive screening of the yield shot has been required to separate the fines and over-sized materials, and the yield of particles of the desired size has been relatively low in relation to the whole amount of comminuted metal. Small particles cannot be used effectively and usually are wasted as impalpable dust, while particles which are too large produce an undue rough or peened effect upon the work which has been grit blasted by them.

The principal objective of this invention has been to provide an apparatus for producing metallic shot particles or pellets which are adapted particularly for blast cleaning and which, as produced, bear a greater uniformity, from particle to particle, than the shot or grit prepared by the past methods. The objective of the invention also has been to provide apparatus which is controllable to produce shot of given particle size with a minimum yield of particles which are smaller and larger than the particles intended to be produced.

In the practice of this invention various metals may be comminuted but the invention is disclosed particularly in relation to the manufacture of pellets of copper alloy suited for use in the cleaning of copper base castings according to the method disclosed and claimed in the copending United States application of Bolton and Weigand Serial No. 81,634, filed March 15, 1949.

In the aforesaid patent application a cleaning or surface treating process is disclosed which imparts a durable surface finish upon castings made of cuprous alloys, which approximates the color

2

of the native metal of the casting and which retains its original grit blasted appearance during processing or storage to much better advantage than the surfaces of similar castings which have been cleaned by the use of the common sand or metal abrasives. The shot disclosed in the aforesaid patent application which has been found to possess this peculiar property, typically but not necessarily, may consist of an alloy of approximately 82½% copper, 14% zinc and 3½% silicon; it preferably ranges in particle size from 20 to 50 AFA sieve mesh and displays a Brinell hardness of substantially 50 to 100.

Shot of this nature, when impacted in a velocity stream against the surface of a casting fabricated of steam or valve bronze, bronze of the Navy M specification, or of alloy A. S. T. M.—D61 or D62, while dislodging any dirt, adherent sand or oxide film that may be present, imparts a surface skin or film having the appearance of the native metal, but this surface does not tend to become smudged or to accumulate dirt as does the surface of a commonly grit blasted casting. Hence, castings treated by the process of the aforesaid patent application retain the pleasing appearance that they possess on leaving the grit blasting machine. Since large quantities of shot of suitable alloy are utilized in the surface finishing of cuprous alloy castings of the type described, in the form of valve bodies, steam fittings, plumbing fixtures and the like, this invention is disclosed particularly in relation to a process for producing suitable alloy abrasives in a convenient manner, with a minimum yield of off-size particles. However, though the invention is disclosed in this environment, the apparatus of the invention is suited for the production of grit particles from metals other than the alloys mentioned specifically.

Briefly, a method using the apparatus of the invention comprises dropping the stream of molten metal, at a given rate, upon a splash plate, sweeping the splashing molten metal from the splash plate by a velocity stream of air substantially coincidental to the spattering of the molten metal on the splash plate and thereby subdividing the splash particles, then freezing and collecting the particles which are so produced. This method has, peculiarly, been found to produce a high yield of particles of given size, even though the particles of spatter as produced by the mere falling of the molten metal are not apparently of uniform size or shape. In any event, through the control of the temperature of the molten metal, the height of fall, the rate of flow of the

molten metal on the splash plate, and the velocity of the sweep stream, finished particles of remarkably uniform size within a given range may be produced. Therefore, the process enables maximum production of shot of substantially uniform size in a given range or size to be obtained.

Apparatus adapted for the practice of the method as described may be simple and inexpensive. A typical production unit is shown, somewhat diagrammatically, in the drawings in which Figure 1 is a cross section and Figure 2 is a top plan view.

In the apparatus shown in the drawings, a splash plate 1 is mounted over a tank or container 2. The splash plate which may be made of steel is inclined toward the inside of the container which is partly filled with water, as indicated by the level 3. A stream of molten metal is furnished to the splash plate from a crucible 4, or other suitable sources, which is constructed and arranged to provide a stream of relatively uniform size or rate of flow, and the source of molten metal is high enough above the splash plate to cause the stream to spatter upon impact with the splash plate. Side plates 5-5 bound the area of impact of the stream of molten metal on the splash plate to prevent side escape of molten particles and to facilitate in their disintegration as discussed at a later point in the specification. Adjacent the area of impact of the molten stream of metal upon the splash plate 1 an air nozzle 6 is arranged to cause a stream of air of substantial velocity to sweep over the surface of the splash plate in a direction substantially parallel to it such that metal falling upon the splash surface, including the spatter, is blown from the plate over the surface of the tank 2.

Below the lower edge of the splash plate, but above the water level in the container, a second steel plate 7 is mounted, this one being angulated slightly upwardly in relation to the water level, the plan configuration of this second plate being in the path of particles which are swept off of the splash plate by the air stream so that metal particles proceeding down the splash plate, substantially in parallelism with it, will be deflected from their path when striking the plate 7. Beyond plate 7 the tank is provided with a baffle 8 which may be in the form of a sheet of metal of semi-circular configuration stood on end vertically in the tank 2. Thus particles projected from plate 7, as well as other metal particles which leave splash plate 1 but never hit the deflector 7 are all caught by the baffle and fall in the water in the tank. A cover plate 9 may be extended across the top of baffle 8 to prevent escape upwardly of the particles.

The splash plate is cooled and spattered with molten metal which is facilitated by maintaining a film of water upon its surface. This is provided through the jet 10 which delivers the water to a point just ahead of the air nozzle 6. The side plates 5-5 are also flushed with water from the side spray jet pipes 11 all of which are connected to a suitable source of supply. Air for the sweep stream furnished by the nozzle 6 is supplied from a suitable compressor, the rate of air flow being controllable by means of valve 12. The rear baffle 8 is also supplied copiously with water from jets 13 which project from a pipe 14 extending across the baffle near its upper end. The surface of this baffle thus has a thin film of water maintained over all of the areas of its surface against which hot or molten particles are blown from the splash plate.

Water is supplied to tank 2 by a jet tube 15 having a regulating valve 16, and is discharged by a drain line communicating with the tank on the side opposite to the tube 15, the rate of drainage being regulated by the valve 17. The jet from the tube 15 prevents undue accumulation of pellets in the water directly adjacent the baffle 8 by washing them to other portions of the tank. The drain valve may be adjusted to prevent the water level in the tank from rising due to the water being drained into it from splash plate 1 and baffle 8; and if necessary, the water stored in the tank may be cooled and agitated by projecting into it a stream of fresh water through jet tube 15, either constantly or intermittently.

When the stream of molten metal from the crucible or supply source hits the splash plate it spatters vigorously, especially in the presence of the water film which is maintained upon its surface. The exact nature of the process of subdivision which occurs is difficult to determine since the atmosphere is be-clouded by steam and particles which are moving at very high velocity. However, it is believed that coincidental with the formation of the spatter, as caused by the falling of the molten metal upon the plate 1, the velocity stream of air issuing from nozzle 6 subdivides the larger splash or spatter globules into smaller sizes since the larger particles, having greater mass, are least cooled, most fluid and, therefore, most susceptible to subdivision. Splash globules which deflect laterally undoubtedly are subdivided upon hitting side plates 5 which also serve to deflect them toward the tank and baffle 8. Additional particles moving downwardly in substantial parallelism with the splash plate 1 are deflected from their path upon striking the plate 7, some of the larger particles also being disintegrated by this impact. Thus, each surface which is struck by a particle of molten metal tends to subdivide the particle. The heavier globules striking plate 1 are subdivided upon impact and the smaller subdivided particles are projected by the air stream directly to the baffle 8 while the larger and heavier ones tend to deflect downwardly upon plate 7. Hence, the heavier subdivided particles, striking the nearer surface (plate 7), will suffer a second impact to cause further size reduction.

Some particles not blown against plate 7 or the rear baffle 8 may fall directly into water in the tank. Inasmuch as the process is characterized by the production of a high percentage of pellets of proper size, and only a small percentage of particles are below the chosen limit, it is believed that the disposition of plate 7 in the line of flight of the heavier pellets minimizes the projection of over-sized shot.

Production of shot particles of a given size is controlled by adjustment of the size of the stream of molten metal and rate of fall as governed by the height of the source of supply over the splash plate, as well as by the pressure or velocity of the air issued from the nozzle 6 and the relative distances and angles of disposition of the splash plate 1 and plate 7.

As one example, in producing shot from the alloy of copper, zinc and silicon adapted to be used in the process of the aforesaid pending patent application, we have found that the alloy may fall from a height of approximately 80", in a stream which is apparently in the neighborhood of $\frac{1}{2}$ " in diameter. The angle of incline of the splash plate may be approximately 75° to the horizontal while the angle of incline of

plate 7 may be approximately 5°. With air supplied to the nozzle 6 at a pressure at 90 lbs. per square inch, substantially two-thirds of the product collected in the tank 2 will be constituted by rounded pellets which will pass a 20 mesh screen but will not pass a 70 mesh screen. In producing pellets from a cuprous alloy of the type described it is preferably to blanket the molten metal in the crucible or container from which it is supplied with a flux consisting of approximately equal parts of borac and sodium carbonate to which 1/4% by weight of lead oxide is added. The flux apparently reduces the surface tension of the molten metal to permit the desired subdivision of particles. Without the flux, the stream of metal does not disintegrate properly upon impact and tends to form a relatively high percentage of elongated particles or particles of fibrous nature.

The foregoing data is given by way of illustration but not by way of limitation. Particles of larger size than those indicated, but having similar uniformity, may be produced by increasing the rate of flow or decreasing air blast pressure. On the other hand, the size of the particles may be decreased by increasing the height of the fall or the air blast pressure or both. Our tests have shown that rounded pellet-like shot containing 50% or more capable of passing 20 mesh screen is desirable for final cleaning of small castings or castings having relatively delicate surface configurations and, in our experience, the height of fall of approximately 80" yields such product in large percentage.

Large quantities of shot of the desired configuration may be furnished with simple apparatus of small size and low cost.

Having described our invention, we claim:

1. An apparatus for manufacturing metal pellets suitable for use in grit blasting operations comprising; a tank adapted to contain a water bath, a baffle at one end of said tank, a splash plate mounted angularly with respect to an end of the tank, in spaced relation to said baffle means mounted above said splash plate adapted to drop a stream of molten metal upon the splash plate from a height sufficient to cause spattering of the stream upon impact with the plate, means for maintaining a film of water upon the surface of the splash plate, means for supplying a blast stream of air across the plate to propel spatter globules from the plate, a deflector plate interposed between the splash plate and baffle at a plane below the splash plate, the deflector plate being angulated in a direction to deflect to the baffle globules which are projected from the splash plate.

2. An apparatus for manufacturing rounded metal pellets for grit blasting operations comprising; a tank adapted to contain a water bath, a relatively flat splash plate mounted over a portion of the tank, the plate being angulated from a horizontal plane toward the opposite end of the tank, a baffle disposed at the opposite end of the tank and having a configuration vertically which presents a concave surface toward the splash plate, a relatively flat deflector plate disposed between the splash plate and baffle at a plane

below the splash plate, the deflector plate being angulated from a horizontal plane toward the splash plate, supply means above said splash plate adapted to drop a stream of molten metal upon the plate to spatter the stream and form globules, means for supplying an air blast across the spatter zone to blow a portion of the globules directly to the vertical baffle and another portion of the globules from the splash plate to the deflector plate and to the baffle by deflection, the concave surface of the baffle being adapted to deflect into the tank the particles propelled at various angles from the splash plate and deflector plate.

3. Apparatus for forming pellets suitable for grit blasting from molten metal, which comprises a water tank having a collector baffle at one portion thereof and a splash plate spaced from the baffle over another portion of the tank, said

20 splash plate being inclined on an angle so as to deflect molten metal falling upon it toward the baffle, the said splash plate being adapted to cause a stream of molten metal falling upon it to spatter into globules, means for providing a 25 blast of air over the surface of the splash plate to sweep spatter therefrom generally in the direction of the baffle, and a secondary impact plate which is disposed above the tank intermediate the said splash plate and the baffle, in position to deflect and coincidentally subdivide relatively larger particles of spatter which are swept from the said splash plate by the air stream.

4. Apparatus for forming pellets suitable for grit blasting from molten metal, which comprises a water tank having a collector baffle at one portion thereof and a splash plate spaced from the baffle over another portion of the tank, said splash

40 plate being inclined on an angle so as to deflect molten metal falling upon it toward the baffle, the said splash plate being adapted to cause a stream of molten metal falling upon it to spatter into globules, means for spraying water over the collector surface of said baffle, means for providing a blast of air over the surface of the 45 splash plate to sweep spatter therefrom generally in the direction of the baffle, and a secondary impact plate which is disposed above the tank intermediate the said splash plate and the baffle, in position to deflect and coincidentally subdivide relatively larger particles of spatter which are swept from the said splash plate by the air stream.
